[57] CLAIM

The ornamental design for an external glazing frame for a window, as shown and described.

DESCRIPTION

FIG. 1 is a perspective view of an external glazing frame for a window showing our new design;

FIG. 2 is a top plan view thereof;

FIG. 3 is an elevational view applicable to all of the top, bottom and sides of the external glazing frame for a window of FIG. 2; and,

FIG. 4 is a bottom plan view of the external glazing frame for a window of FIG. 1.

1 Claim, 4 Drawing Sheets

FIG. 2

FIG. 3

FIG. 4
